HERBERT T. WHALER, OF MIAMI, FLORIDA.

RADIO DIAL.

Application filed March 30, 1923. Serial No. 628,827.

To all whom it may concern:

Be it known that I, HERBERT T. WHALER, a subject of the King of Great Britain, residing at Miami, in the county of Dade and State of Florida, have invented a new and useful Improvement in Radio Dials, of which the following is a specification.

This invention relates to an improved radio dial which is adapted to be used for obtaining the proper adjustment of the spindle of the rheostat, tickler coil, condenser, variometer or coupler of a radio receiving set, or in connection with the rotatable adjustment of any other spindle where extreme precision, as well as a wide range of adjustment is desirable.

The general object of the invention is to provide means for effecting adjustments of great precision which is releasable in order to permit a rough adjustment through a wide angle to be quickly made.

With this object in view, the invention includes a relatively fixed disk that is secured to the panel through which the rotatable spindle projects, which disk is provided with a recess in which operates a dial secured to the spindle of the instrument and having a peripheral worm gearing, a portion of the disk adjacent the periphery of the dial being cutaway and having a journal block pivoted therein, in which is journaled a worm adapted to mesh with the peripheral teeth of the dial to effect accurate adjustments of small range, said worm being yieldably held so as to be readily disengageable when a different adjustment through a wide angle is desired.

The structural details of the invention will be best understood from a consideration of the following description, taken in connection with the accompanying drawing, which illustrates the preferred form of the invention.

In the drawing:—

Fig. 1 is a front elevation of the improved dial showing a portion of the panel in front of which the dial is mounted.

Fig. 2 is a sectional view taken parallel to the face of the panel.

Fig. 3 is a section on the line 3—3 of Fig. 1.

Fig. 4 is a section on the line 4—4 of Fig. 2.

Fig. 5 is a detail sectional view showing the block in which the worm is journaled.

Fig. 6 is a detail view showing the means for disconnecting the worm gearing.

Fig. 7 is a detail perspective view of the worm and its bearing.

Fig. 8 is a detail perspective view of the cam plate for disconnecting the worm gearing.

Referring in detail to the drawing, 10 designates the panel of a radio receiving set or other instrument, in connection with which the invention may be used, and 14 65 designates a spindle which is connected to the mechanism to be adjusted. In carrying out the invention, a disk 11 is secured to the front face of the panel in spaced relation thereto, this disk having a peripheral flange 12 forming a circular recess which is adapted to receive a dial 13 that rotates with the spindle 14 and provides means for measuring the angular position thereof.

The means for connecting the dial 13 75 with the spindle 14 includes a sleeve 15 secured to the spindle 14 by a set screw 16 or the like, and having a threaded outer portion which is threaded into a central opening through the dial 13. A circular 80 concave resilient plate 17 is secured to the sleeve 15 and engages in a circular shouldered recess 18 in the bottom of the disk 12 to provide sufficient friction to retain the dial 13 and spindle 14 against accidental 85 movement, and the tension of the plate 17 may be adjusted by turning the dial on the threaded end of the sleeve 15. After the proper adjustment of the tension plate has been secured, the dial may be locked to the 90 spindle by the knob 19 which is threaded to the sleeve 15 and acts as a lock-nut. After the dial has been secured in proper position on the sleeve, and the latter secured to the spindle by means of the set 95 screw 16, the whole assembly is firmly secured together by a screw 20 that is driven through the end of the knob 19 and into the internally threaded end of the spindle 14.

For the purpose of effecting the finer adjustments of the spindle, the dial is provided with a peripheral groove in which is formed a series of concave worm gear teeth 21 adapted to mesh with and be driven by a worm drive 22 which is journaled in a 100 bearing block 23. The side of the disk 12 is formed with a recess 24 adjacent one side of the dial, within which the journal block 23 is pivoted at one end, as shown at 25, whereby the block is permitted to swing 110 outwardly as indicated by dotted lines in Figs. 2 and 6, to permit the worm drive

to be disengaged from the teeth 21, so that a rough adjustment of the spindle may be quickly secured by a rotation of the knob 19.

The worm drive spindle is provided near 5 its outer end with a reduced portion 26 which is engaged by a coiled spring 27 to yieldingly hold the worm gearing in its normal position of engagement. The spring 27 extends substantially at right angles to 10 the worm spindle and is housed within the flange 12 of the disk 11, and has its inner end embedded therein as shown at 28. The extremity of the worm spindle is provided with a knob 29 by means of which it may 15 be easily moved manually to effect the finer adjustments.

The journal block 23 is also provided with a laterally-projecting pin 30, a notch 31 being cut in the edge of the disk 11, as shown 20 in Fig. 6, for permitting the inward movement of the journal block to permit the engagement of the worm gearing. A cam plate 32 is pivotally mounted at 33 on the inner surface of the disk 11, and is provided with an outer inclined cam edge 35, which, as the plate is swung about its pivot, 25 engages the under side of pin 30 to raise the worm out of engagement with the gear teeth 21. The outer end of the plate 32 is 30 provided with an arcuate edge 36 which, as the plate approaches the position shown by dotted lines in Fig. 6, rides underneath the pin 30 and locks the gearing in its disengaged position. A wing 37 is formed on 35 the other end of plate 32 to limit the inward movement thereof, and also to provide convenient means for obtaining hold of the same to release the worm and permit it to re-engage the teeth 21.

40 The dial 13 is provided with the usual graduations 38, and the adjacent surface of the flange 12 is provided with a series of graduations 39 having similar major subdivisions, but with the minor sub-divisions 45 bearing a vernier relation to the graduations 38, whereby adjustments of the greatest precision may be effected.

While I have described the invention particularly with reference to a radio-receiving set, it will be apparent that the principles 50 of the invention may be used in connection with other instruments wherever adjustments of a spindle or other rotatable element are desired and where great precision, 55 as well as a wide range of adjustments are required. It will also be understood that while I have shown and described the structural details of one form in which the invention may be embodied, various modifications 60 may be made therein within the scope of what is claimed, without departing from the spirit of the invention.

What is claimed is:—

1. In an instrument having a panel and 65 a projecting spindle mounted for rotary ad-

justment, the combination of a disk having a cylindrical recess in its outer face, means for securing the disk to the panel with the spindle projecting centrally therethrough, a dial adapted to be secured to the spindle to 70 rotate in said recess, said dial having peripheral worm gear teeth, a bearing block pivotally mounted within the rim of said disk, a spindle journaled in the bearing block and having a driving worm yieldably held in engagement with said worm gear teeth for effecting fine adjustment of the dial, and a knob for effecting rough adjustment thereof when the worm gear is disconnected. 75

2. In an instrument having a panel and a projecting spindle mounted for rotary adjustment, the combination of a disk having a cylindrical recess in its outer face, means for securing the disk to the panel, with the 80 spindle projecting centrally therethrough, a dial adapted to be secured to the spindle to rotate in said recess, said dial having peripheral worm gear teeth, a bearing block pivotally mounted within the rim of said 85 disk, a spindle journaled in the bearing block and having a driving worm engageable with the worm gear teeth, a coiled spring housed within the disk substantially at right angles to the worm spindle and normally holding the worm gear in engagement for effecting fine adjustment of the dial, and a knob secured to the outer end of the spindle for effecting rough adjustment thereof when the worm gear is disconnected. 90

3. In an instrument having a panel and a projecting spindle mounted for rotary adjustment, the combination of a disk having a cylindrical recess in its outer face, means for securing the disk to the panel with the 105 spindle projecting centrally therethrough, a dial adapted to be secured to the spindle to rotate in said recess, said dial having peripheral worm gear teeth, a bearing block pivoted to the disk and having a worm drive journaled therein, a coil spring housed within the disk substantially at right angles to the worm drive and normally urging the worm drive into engagement with the peripheral teeth of the dial, and a lever pivoted to the disk and having a cam edge engageable upon movement of the lever with a portion of the bearing block to move and lock said worm drive out of engagement with the dial teeth. 115

4. In an instrument having a panel and a projecting spindle mounted for rotary adjustment, the combination of a disk having a cylindrical recess in its outer face, means for securing the disk to the panel, with the 120 spindle projecting centrally therethrough, a dial adapted to be secured to the spindle to rotate in said recess, said dial having peripheral worm gear teeth, a bearing block pivotally mounted within the rim of said 125 disk.

disk, a worm drive journaled in the block, a coiled spring housed within the disk substantially at right angles to the worm drive and normally holding the latter in engagement with the dial teeth, said bearing block having a laterally projecting pin, and a lever having a cam edge engageable with the pin to move and lock said worm drive out of engagement with the dial teeth.

5. In an instrument having a panel and a projecting spindle mounted for rotary adjustment, the combination of a disk, means for securing the disk to the panel, with the spindle projecting centrally therethrough, a

dial, means for securing the dial to the spindle to rotate adjacent to said disk, said dial having peripheral worm gear teeth, a worm drive normally held in engagement with the peripheral teeth of the dial, and a cam plate pivoted to the disk on an axis parallel to the spindle and movable to disconnect the worm drive from the gear teeth and to lock the same in disengaged position.

In testimony, that I claim the foregoing as my own, I have hereto affixed my signature.

HERBERT T. WHALER.
